VALVE

Lloyd Hornbostel, Beloit, Wis., assignor to Beloit Iron Works, Beloit, Wis., a corporation of Wisconsin

Application October 23, 1940, Serial No. 362,361

6 Claims. (Cl. 251—8)

This invention relates to a valve especially adapted for controlling the flow of liquid suspensions in conduits without creating eddy currents, pockets and the like when partially closed to throttle the flowing suspension material.

More specifically the invention relates to a throttling valve for controlling streams of paper stock, white water and the like suspensions without forming pockets or "dead" areas where lumps of fibers can collect, and without setting up a churning action in the streams.

While the invention will hereinafter be described in connection with valves for controlling flowing streams of paper stock, white water and the like suspensions which must be handled in a paper mill, it should be understood that the valves of this invention are not limited for such use and are capable of controlling the flow of any fluid.

The conventional valves that have been used in stock and white water conduits have been either of the movable plug type or gate type. These valves are objectionable because, when partially closed, they form pockets in the flowing stream where lumps of stock can collect. In addition, these types of valves set up a churning action in the conduit in back of the valve which renders it very difficult to obtain even distribution of the flowing material in branch pipes located after the valve.

It is highly important that stock flowing through conduits to a paper machine be positively controlled or throttled to any desired extent without the formation of pockets in the flowing stream and without the setting up of a churning action in the stream. It is also very important that the throttled stock flow evenly to various branch lines in the conduit so as to obtain even distribution of stock in all branches.

These problems occur in many places in a paper mill, such as, for example, in the stock line going to two or more pulp screens, and in the conduit direct from the stock fan pump to the head box of the paper machine.

The valves of this invention eliminate the formation of any pockets or "dead" areas in the conduits in which they are mounted and maintain a uniform type of flow in these conduits even when partially closed to cause a throttling effect. Branch pipes leading from the conduits containing a valve of this invention will receive equal amounts of stock and even distribution through the branch pipes will be maintained.

The valves of this invention include a streamlined central member fixed in the center of a

flowing stream so that the flowing material will surround the member without creating eddy currents, "dead" spaces or the like disturbances. The fixed member is encased in a slidable shell which can be shifted longitudinally to move a portion thereof toward and away from the fixed member, thereby decreasing or increasing the capacity of the passageway around the fixed member. The variation of the size of the passageway creates a throttling action on the flowing stream and the stream flow can be stopped entirely by moving the shell into seating engagement on the fixed member.

It is, then, an object of this invention to provide a valve for controlling flowing streams of solids in liquid suspensions without effecting disturbances in the flowing streams.

A further object of this invention is to provide a throttling valve adapted for controlling flowing streams of paper stock without permitting the collection of lumps of stock fibers.

A further object of the invention is to provide a valve wherein the valve housing or casing is longitudinally shiftable to control the valve setting.

Another specific object of this invention is to provide a throttling valve having a streamlined or tear-drop shaped fixed member and a longitudinally shiftable shell member movable toward and away from the fixed member.

Other and further objects of this invention will be apparent to those skilled in the art from the following detailed descriptions of the annexed sheets of drawings which disclose preferred embodiments of the invention.

On the drawings:

Figure 1 is a side elevational view of a valve according to this invention mounted for use between opposed conduits of a pipe line.

Figure 2 is a longitudinal vertical cross-sectional view taken along the line II—II of Figure 1.

Figure 3 is a transverse vertical cross-sectional view taken along the line III—III of Figure 2.

Figure 4 is a fragmentary side elevational view of a modified form of valve construction according to this invention.

Figure 5 is a longitudinal vertical cross-sectional view taken along the line V—V of Figure 4 and also illustrating a portion of the valve construction omitted from Figure 4.

As shown on the drawings:

In Figures 1 to 3 inclusive the reference numeral 10 designates generally a valve according to this invention mounted between spaced op-

posed conduits or pipes 11 having outturned flanges 12.

A hollow cylindrical end piece 13 of the valve 10 has an outturned flange 14 bolted to the flange 12 of the adjacent conduit 11. A similar hollow cylindrical end portion 15 is provided at the other end of the valve. This cylindrical piece 15, however, has a circumferential groove 16 near its outer end receiving the tongue 17 formed on the end flange 18 of a split collar 19. The end flange 18 is bolted to the flange 12 of the adjacent conduit 11. As shown in Figure 1, the collar 19 is split as at 20 and is provided with outturned flanges 21 which are drawn together by bolts as shown.

The flange 18 of the collar 19 holds the main body of the collar in spaced relation from the end piece 15. This main body portion of the collar is internally threaded as at 22 (Figure 2).

The end pieces 13 and 15 are connected through fins 23 and 24 respectively to a hollow tear-drop shaped plug 25 as best shown in Figure 2.

Actually the cylindrical end pieces 13 and 15, the fins 23 and 24, and the plug 25 can be considered as one unit with the plug member 25 disposed in a stream flowing between the conduits 11 and with the fins permitting free passage of the stream. This one-piece structure is secured to the conduits 11 and fits between the outturned flanges 12 of the conduits.

The plug 25 has a raised annular seat portion 26 on the leading end thereof at a point substantially in line with the end piece 15.

A spherical shaped shell or housing 30 encases the plug 25 and has cylindrical hollow end portions 31 and 32 slidably mounted on the end pieces 13 and 15 respectively. The end portion 31 has an offset rim 33 providing a recess 34 for a packing ring 35. The packing ring is held in the recess 34 by a ring 36 bolted to the rim 33 and adapted to project into the recess 34 for compressing the packing 35.

The cylindrical end portion 32 of the shell 30 has an offset rim 37 which is externally threaded at 38 into the collar 19. This offset rim 37, like the rim 33, provides a recess 39 for a packing ring 40. The packing ring 40 is held in the recess by a metal ring 41 bolted to the rim 37 and adjustable to compress the packing.

The shell 30 has a plurality of solid spokes 42 and hollow spokes 43 radiating from the central portion thereof as shown in Figures 2 and 3. An annular rim 44 circumscribes the spokes and is apertured at each hollow spoke 43 so that a lever bar 45 can be inserted into a hollow spoke if desired.

An annular seat 46 is formed on the interior of the casing at the inner end of the cylindrical portion 32 thereof as shown in Figure 2.

From the above descriptions it will be understood that the internally threaded collar 19 is secured on the flange 12 of a fixed conduit 11. The casing 30 has a threaded rim portion 37 on one end thereof threaded into the collar 19. Therefore, when the casing 30 is rotated the end portions 31 and 32 thereof will slide over the fixed cylindrical end pieces 13 and 15 of the plug assembly. The casing is thus longitudinally shiftable between the outturned flanges 12 of the fixed conduits 11 and can move from a fully opened position shown in solid lines in Figure 2 to a fully closed position shown in dotted lines in Figure 2. In the fully closed position the seat 46 of the casing engages the seat 26 of the plug.

The collar 19 is split as at 20 and can be spread to remove the tongue 17 thereof from the groove 16 of the end piece 15. The collar, therefore, can readily be disassembled so that the packing 5 40 can be replaced.

Ordinarily, the shell 30 can be rotated by manual forces exerted on the rim or hand wheel portion 44 thereof. However, in the event that the casing should become stuck, the lever bar 10 45 can be inserted in a hollow spoke and an enhanced leverage obtained for loosening the casing.

Stock flowing in the direction indicated by the arrows in Figure 2 will enter the valve without 15 being subjected to any obstructions. As indicated in Figure 2, the inside diameter of the cylindrical end piece 15 is exactly the same as the inside diameter of the conduit 11 and no obstruction is provided in the path of the incoming stream. The stream then flows past the fins 24 which are relatively thin and have rounded leading edges which will not impede the flowing material. The stream is then gently deflected by the leading end of the tear-drop shaped plug 25 to flow through the annular passage 47 provided between the plug 25 and the spherical casing 30. This annular passage bows the stream outwardly beyond the passage provided by the conduits 11 and can be varied in capacity to 30 provide any desired throttling action on the stream.

After the stock flows beyond the seat 26 of the plug it is then directed inwardly along a streamlined path which will not cause disturbance of the stream. The stock then flows past the fins 23 and into the other conduit 11.

The throttling action made possible by valves of this invention can be exactly controlled, since the casing can be shifted any desired amount between a fully opened position and a fully closed position.

The valve 10 shown in Figures 1 to 3 has a tear-drop shaped plug 25 which is especially adapted for use in fluid streams which flow only in the direction shown by the arrows in Figure 2. In the event, however, that the valve is to be used in a pipe line wherein the fluid streams may flow in either direction, the modification shown in Figures 4 and 5 is desirable. In these figures, parts substantially identical with parts shown and described in Figures 1 to 3 have been identified with the same reference numerals.

The valve 10a shown in Figures 4 and 5 has a plug 25a shaped somewhat differently than the tear-drop plug 25 in the valve 10 of Figures 1 to 3. The plug 25a is constructed in the same manner as the plug 25 and is connected through the same type of fins 23 and 24 to the cylindrical end pieces 13 and 15. However, both ends of the plug 25a converge to a point, whereas the plug 25 only has the tail end converging to a point. The plug 25a is thus adapted to present pointed leading ends to fluid flowing in either direction through the conduits 11.

The valve 10a also has a somewhat different shifting mechanism for the casing 30 thereof. In the valve 10a the cylindrical end portion 32 of the casing 30 has a rack 50 built up thereon. This rack extends from the rim portion 37 to the spherical portion of the casing.

The flange 18 is split and connected to the cylindrical end piece 15 through the groove and tongue 16 and 17 in the same manner as described above, but the circumscribing collar 19 is 75 replaced with a housing 51 formed integrally

with the flange but projecting only over the rack 50. This housing rotatably supports, at its inner end, a shaft 52 on which is secured a pinion 53 meshing with the teeth of the rack 50. The housing 51 provides bosses 54 on each side of the rack in which the shaft 52 is rotatably mounted. A hand wheel 55 is secured on the outer end of the shaft 52 for facilitating rotation of the shaft.

Rotation of the pinion 53 will move the rack 50 to slide the shell or casing 30 on the end pieces 13 and 15 so as to move the seat 46 of the casing toward and away from the seat 26 of the plug 25a. The casing 30 is therefore shifted without rotation and the rim 44 may be dispensed with. However, since the casing may get stuck on the end pieces 13 and 15, the rim 44 may prove useful in loosening the casing so that the rack and pinion can be freely operated.

From these descriptions it will be clearly understood that the valves of this invention include fixed plugs disposed in a flowing stream in such a manner as to prevent disturbances in the stream. The casings of the valve are longitudinally shiftable to obtain any desired throttling action on the flowing stream. The general design of the valve lends itself very well to manufacture at low cost. The valve can be made up of non-corrosive material such as brass, or can have an all-iron construction and be rubber-lined if corrosive fluids are to be passed through the valve.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A throttling valve comprising a hollow cylindrical end piece having an outturned flange for fixed connection with a conduit, a fin secured to the interior of said end member and projecting beyond the end member away from said flange, a hollow plug member secured on said fin, a second fin projecting from the other end of the plug member, a hollow cylindrical end piece secured on said fin in spaced relation from said plug member, said second end member having a peripheral groove therearound, a flange engaged in said groove adapted for attachment to a second conduit, a spherically shaped hollow casing enveloping said plug and having cylindrical end portions slidable on said cylindrical hollow end members, and toothed means between said groove engaged flange and one of said cylindrical end portions of the casing for longitudinally shifting the casing to move the same toward and away from the plug.

2. A valve comprising a streamlined plug having an annular seat therearound, fins projecting laterally from the ends of the plug, hollow cylindrical end members surrounding said fins, a shell encasing said plug and slidable on said end members, a collar mounted on one of said end members and enveloping one end of said casing in screw thread relation with said end of the casing and means for rotating the casing to longitudinally shift the same relative to the plug.

3. A valve comprising a plug streamlined for

- fluid flow therearound, fins extending from the ends of the plug presenting narrow edges only to fluid flowing toward and away from the plug, hollow cylindrical end portions carried by said fins in spaced relation from each other and from the plug at each end portion of the plug, a casing enveloping said plug and bridging the space between the end portions, said casing having cylindrical end walls slidably mounted on said cylindrical end portions, seals carried by the cylindrical portions of the casing acting on the cylindrical end portions to prevent leakage of fluid from the casing, a removable collar mounted around one cylindrical end portion adapted to be secured to a pipe, tooth means carried by said collar, tooth means on the cylindrical end portion of the casing in engagement with said collar tooth means, and means for effecting relative movement between the tooth means to longitudinally shift the casing on the cylindrical end portions whereby the casing is moved toward and away from the plug to vary the capacity of the passageway provided between the plug and casing.
4. A throttling valve comprising a plug streamlined for fluid flow having fins projecting from the ends thereof and cylindrical end portions carried by said fins in spaced relation from the plug and from each other, said fins presenting narrow edges only to fluid flow around the plug, one of said cylindrical end portions having a removable collar disposed therearound, a casing bridging the space between said cylindrical end portions and having cylindrical end walls slidably mounted on the end portions, one of said cylindrical end walls of the casing extending into the removable collar in screw-thread relation therewith, means facilitating rotation of the casing around the plug and cylindrical end portions whereby the screw-thread relation between the collar and casing will effect a longitudinal shifting of the casing to vary the capacity of the passageway between the casing and plug.
5. A valve comprising a pair of spaced hollow end members, a plug carried by said members and disposed therebetween, a casing surrounding the plug and movably mounted on the end members to define a passageway around the plug and between the members, seals between the end portions of the casing and said end members to prevent leakage of fluid from the casing, a removable collar mounted around one end portion, and means between said collar and said casing for shifting the casing on the end members to vary the capacity of the passageway whereby said collar is adapted to be removed from said end member for facilitating replacement of the seal.
6. A valve comprising a pair of spaced hollow end members, a plug between said end members, fins connecting said plug with the end members, a casing surrounding the plug and movably mounted on the end members to define a passageway around the plug and between the members, a collar disposed around one of said end members and having a portion overlapping the portion of the casing which is mounted on said end member, and means between said casing portion and the overlapping collar for shifting the casing to vary the capacity of the passageway.
